UNITED STATES PATENT OFFICE

2,326,271

DENTAL VULCANIZING FLASK

Ernst Wessinger, Long Island City, N. Y.

Application January 22, 1942, Serial No. 427,737

1 Claim. (Cl. 18—33)

This invention relates to dental flasks of sectional construction adapted for holding artificial teeth while being vulcanized to dental plates.

An object of the invention is to provide a flask having separable elements so arranged that they may be opened or closed without displacing or disturbing the moulding material or the model set therein.

A further feature is in the provision of means whereby the moulding material may be easily entered or removed without fracture.

Another purpose is to produce a dental flask of sturdy construction, easily and quickly operated and capable of long continued service.

Finally, it is an aim to furnish a flask particularly adapted for use in connection with improved dental plates described in my copending application, filed June 19, 1941, Serial No. 398,719, and in which suction inserts are embedded in the plate.

These and other advantageous objects are accomplished by the novel and practical construction, combination and arrangement of simple parts hereinafter described and illustrated in the annexed drawing, constituting a component of this disclosure, and in which:

Figure 1 is a top plan view of a fully assembled embodiment of the invention.

Figure 2 is a front elevational view of the same, partially in section.

Figure 3 is a plan view of the hingedly connected hollow body portion as in closed position.

Figure 4 is a similar view of the same shown in an open position.

Figure 5 is a horizontal sectional view looking on line 5—5 of Fig. 2.

Figure 6 is a transverse sectional view taken on line 6—6 of Fig. 3.

Figure 7 is a similar sectional view taken on line 7—7 of Fig. 5.

Referring in detail to the drawing, the numeral 15 designates the lower base element of the flask, an irregularly shaped hexagonal cup in shape, having convergent side walls 16 terminating in a flat bottom 17.

At the upper edge of the walls is a small outstanding flange 18 acting as a reinforcement.

Extending radially outward from the front of the base, and also from its main opposed sides, are integral lugs 19 containing open recesses 20, adapted to receive the square heads 21 of screw bolts 22. At opposite sides, adjacent the rear lugs 19, are narrow radial slots 23, formed through the flange 18 and partially in the walls

5 The main or body portion 25 of the apparatus is composed of two opposed wing-like side elements, respectively 26 and 27, shaped in conformity with the lower or base element, except that their side walls converge upwardly.

These wing elements are pivotally connected at their rear ends by a pin 28, while at their front ends are forked extensions 29 and 30. A clamp bolt 31 is pivoted on a pin 32 set in the fork 29, and provided with a wing nut 33 to draw the wings towards each other, in which position there is a space 34 for the bolt 22.

Extending from the wings 26 and 27 are slotted pads 35 to receive the bolts 22 at the rear portion of the device.

10 Adjacently in front of the pads 35 are down-reaching guide lugs 36 adapted to engage in the slots 23, thereby to correctly position the body 25 on the base 15.

15 Over the hollow body 25 is disposed a flat topped cover 40, of the same general outline as the hinged elements when closed; this cover may have down-reaching flanges 41 to act as guides, and are provided with openings through which the bolts 22 pass, the bolts having nuts 42, whereby to bind the structure firmly together when in use.

20 In operation, the base element 15 is supplied with a plastic material, as plaster of Paris, into which the model is set, and then levelled off.

25 The mating model is properly positioned, with respect to that in the base, and filled therearound with a similar plastic material. Thereafter, the wing elements 26 and 27 are closed inwardly, the mould levelled and the cover clamped in position; obviously the models are released in a reverse manner.

30 Having thus described the invention, including its construction and application, what is claimed as new and sought to secure by Letters Patent, is:

35 A dental flask comprising a cup-shaped pentagonal base having convergently inclined walls, a two part hingedly connected hollow body having reversely inclined walls to fit thereon, cooperative means on said base and body to cause mutual alinement, a flange on said cover to clampingly extend over said body when assembled means to clamp the parts of said body when in closed relation, a cover having guide flanges to suit said body when closed, bolts having heads set permanently in said base to extend upward exteriorly said body through said cover, and nuts for said bolts to clamp all of said elements in operative relation.

50 55 ERNST WESSINGER.
